CLAIM

The ornamental design for a device for making frozen confections, as shown and described.

DESCRIPTION

FIG. 1 is a perspective view of my new, original, and ornamental design for a device for making frozen confections;

FIG. 2 is a perspective view of a single compartment separated from the device for making frozen confections;

FIG. 3 is a front view of the device of FIG. 1. The undisclosed rear view is not being claimed;

FIG. 4 is a bottom view of the device of FIG. 1, when viewing FIG. 1 on a horizontal plane;

FIG. 5 is a bottom view of the device of FIG. 1, when viewing FIG. 1 on a vertical plane;

FIG. 6 is a top view of the device of FIG. 1, when viewing FIG. 1 on a horizontal plane;

FIG. 7 is a top view of the device of FIG. 1, when viewing FIG. 1 on a vertical plane; and,

FIG. 8 is a side view of the device of FIG. 1.
